UNITED STATES PATENT OFFICE.

WALTER E. LOMBARD, OF ARLINGTON, MASSACHUSETTS.

LIFTING-JACK.

1,396,858.

Specification of Letters Patent. Patented Nov. 15, 1921.

Application filed April 1, 1921. Serial No. 457,758.

To all whom it may concern:

Be it known that I, WALTER E. LOMBARD, a citizen of the United States of America, and a resident of Arlington, in the county 5 of Middlesex and State of Massachusetts, have invented certain new and useful Improvements in Lifting-Jacks, of which the following is a specification.

This invention relates to lifting jacks and 10 particularly screw jacks which are adapted to lower under the weight of the load.

The primary object of the present invention is the provision of means whereby the speed of lowering may be controlled by hydraulic means.

The invention consists in certain novel features of construction and arrangement of parts which will be understood readily by reference to the description of the drawings and to the claims to be hereinafter given.

For the purpose of illustrating the invention, one preferred form thereof is illustrated in the drawings, this form having been 25 found to give satisfactory and reliable results although it is to be understood that the various instrumentalities of which the invention consists can be variously arranged and organized and the invention is not limited to the precise arrangement and organization of these instrumentalities as herein described and shown except as required by the scope of the appended claims.

Of the drawings:

35 Fig. 1 represents an elevation of a lifting jack embodying the principles of the present invention.

Fig. 2 represents a vertical section of the same.

40 Fig. 3 represents a partial plan of same, a portion thereof being shown in section, and

Fig. 4 represents an enlarged vertical section on line 4, 4, on Fig. 3.

Similar characters indicate like parts 45 throughout the several figures of the drawings.

In the drawings, 10 is a base having an upwardly projecting threaded extension 11 on which is mounted a casing 12 having laterally projecting rectangular flanges 13 and 50 14 preferably opposite to each other and surrounding openings 13^x and 14^x giving access to the interior of said casing.

In a depression 15 in the extension 11 is 55 disposed a bearing plate 16 having an annular groove in the upper face thereof in

which is positioned a plurality of anti-friction members 17, the upper portions of which extend into an annular groove in a plate 18 surrounding the hub of a bevel gear 19. 60

The plate 18 is provided with an apron 20 surrounding the anti-friction members 17 and the lower end of which is closely adjacent the upper face of the plate 16 thereby preventing dust and other foreign 65 substances from coming into contact with the anti-friction members 17.

Centrally disposed in the base 10 is the squared member 21, the flat side faces of which coacting with the walls of the opening in the base of which said member is fitted, prevent said member from rotating about its axis.

This member 21 is provided with a cylindrical extension 22 projecting upwardly 75 through the plate 16 and terminating in a reduced cylindrical portion 23 fitted to the bore of the lifting screw 24.

This lifting screw 24 is provided at its upper end with a flanged head 25 disposed 80 in a recess in the upper end of the cylindrical load-supporting member 26.

This member 26 is secured to the head 25 by means of screws 27.

The load-lifting member 26 is provided 85 with a tubular extension 28 extending downwardly and surrounding the barrel 29 having secured in its upper end a nut 30 coacting with the lifting screw 24.

The lower end of the barrel 29 is provided 90 with a hub 31 to which the gear 19 is secured.

The member 21 is prevented from being displaced by means of the screws 32 extending through the flange thereof into the 95 base 10.

Meshing with the gear 19 is a bevel pinion 33 having a cylindrical shank 34 revolvable in a bearing 35 in the plate 36 closing the rectangular flanged opening 13^x. 100

Keyed to the shank 34 of the gear 33 is a spur gear 37 meshing with a pinion 38 on the operating shaft 39 extending through a bearing 40 in the plate 36.

The outer end of the shaft 39 has mounted thereon, an operating mechanism 41 which may be of any well-known construction provided with means for disconnecting it from the shaft 39 when it is desired to lower the load. 105

It is obvious that when the pinion 38 is rotated by means of the operating mecha-

nism 41, rotary movement will be imparted to the gear 19 through the gears 37 and 33 and the nut supporting barrel 29 will be rotated about its axis in a contra-clockwise direction and the screw 24 and load-supporting member 26 will be moved upwardly on the cylindrical portion 23 and lift the load to any desired height.

The member 26 is provided with lateral 10 depressions 42 by which the member 26 and tubular extension 28 may be adjusted vertically relatively to the screw 24 when no load is being supported thereby.

The upper end of the casing 12 is cylindrical and has a bearing face 43 which serves 15 as a guide for the extension 28 as it is reciprocated vertically.

The lower end of this extension 28 is also provided with a bearing surface 44 which 20 fits the periphery of the barrel 29.

It is obvious therefore that during the lifting of the load the load-lifting member 26 is guided by the bearing surface 43 at the upper end of the casting 12 and by the bearing surface 44 on the periphery of the barrel 29 while the cylindrical portion 23 extending upwardly into the bore of the screw 24 serves as an additional guide.

By this means a very rigid support is 30 given to the load-lifting member in whatever position it may be during the lifting operation.

When the load is supported by the member 26 it will be prevented from rotating by 35 means of the weight thereon and consequently when the nut 30 is rotated the screw 24 will be compelled to move upwardly.

The flange 14 has secured thereto a closing plate 45 having a bearing 46 in its lower end 40 in which is mounted the shank 47 of a pinion 48 meshing with the bevel gear 19.

The plate 45 also has mounted therein a revoluble shaft 49 having a worm 50 thereon meshing with a worm gear 51 secured to 45 a shank 52 on a pinion 53 meshing with a gear 54 having pivoted thereto, pawls 55 engaging a ratchet 56 secured to the shank 47 of the bevel pinion 48.

By means of this construction the gear 50 48 is free to turn about its axis, in one direction, during the lifting operation without transmitting movement to the worm 50 and the intermediate gears 51, 53 and 54.

When, however, the load is being lowered 55 under its weight, the downward movement of the screw 24 will rotate the worm 30 in the opposite direction, this rotary movement being transmitted through the gears 19 and 48, pawls 55, gears 54, 53, 51 to the worm 50 thereby causing said worm shaft 49 to be rotated.

The closing plate 45 has formed thereon a chambered extension 57 having a cylindrical chamber 58 in which is mounted an eccentric 65 59 secured to the end of the worm shaft 49.

The chamber 58 is closed by the plate 60 secured to the casing 57 by bolts 61.

The shaft 49 is in axial alinement with the center of the chamber 58 and surrounding the eccentric 59 is an annular piston 62 70 the periphery of which is continually in contact with the inner wall of the chamber 58 at some point during the rotation of the shaft 49.

The casing 57 has mounted therein an oscillating, cylindrical, slotted member 63 in the slot 64 of which reciprocates the radial blade or extension 65 formed upon the annular piston 62. 75

This radial blade or extension 65 has a 80 fluid passage 66 extending therethrough and communicating at its outer end with one end of a chamber 67, the opposite end of which communicates with a valve chamber 68.

In the valve chamber 68 is a cylindrical 85 bushing 69 in which the valve 70 is mounted, said bushing being provided with a plurality of ports adapted to register with ports in the valve 70.

The valve 70 is provided with a port 71 90 communicating with the chamber 67 and a port 72 communicating with the chamber 58.

It also has a port 73 communicating with a passage 74 partially surrounding the cylindrical chamber 58, said passage 74 having a reverse bend at 75 and terminating 95 near the valve 70 at 76.

The casing 57 has upwardly projecting ears 77 provided with bearings in which is mounted the revoluble shaft 78 having an 100 operating head 79 secured to one end thereof and a washer 80 at the other end thereof, this washer 80 with the head 79 preventing end movement of said shaft 78.

Between the ears 77, the shaft 78 is provided with a helical thread 81 on which is adapted to be reciprocated a nut 82 having trunnions 83 extending into slots 84 formed in the end of an arm 85 secured to the reduced end 86 of the valve 70. 105

It is obvious that by rotating the operating head 59, the nut 82 will be moved endwise of the screw 81 causing the arm 85 to be oscillated about its pivot thereby effecting the oscillation of the valve 70 about its axis 115 to close the ports 71 and 72 or open them to any desired degree.

When the member 26 has been raised to the desired point, the valve 70 is closed and the lifting mechanism is disengaged from 120 the shaft 39.

As the interior of the chambers 58-67 and passage 74 are completely filled with liquid, it is obvious that the eccentric will be prevented from rotation about the axis of the 125 shaft 49 as long as the valve 70 remains closed and consequently the load will be retained in elevated position.

During the lowering of the load the shaft 49 is rotated in the direction of the arrow α 130

on Fig. 4 and as soon as the valve 70 is opened the liquid in the chamber 58 in advance of the piston 62 will be free to pass through the passage 66, chamber 67 and valve 70 to the chamber 58 on the opposite side of piston 62.

It is self evident that if the valve 70 is fully opened the load will lower rapidly while if only partially opened the rotation 10 of the piston 62 will be retarded and the load will be lowered at a decreased speed.

Consequently the setting of the valve 70 will provide a very effective means for controlling the downward movement of the 15 member 26 under its load so that any predetermined speed may be attained.

The passage 74 may be dispensed with if desired but preferably this passage is provided to take care of any surplus liquid in 20 case the port 72 should become closed before the closing of the port 71 in which case a portion of the liquid in advance of the piston 62 will be forced into the passage 72 under more or less compression.

25 As soon as the port 72 is again opened a portion of the liquid in the passage 74 will be free to pass through the valve and its port 72 into the chamber 58.

It is self evident that the port 73 to the 30 passage 74, is open at all times without regard to the position of the valve 70.

By means of this invention there is provided a hydraulic control for lifting jacks which is positive in operation and which 35 may be quickly set to permit the lowering of the load at any desired speed.

It is believed that the operation and many advantages of the invention will be understood without further description.

40 Having thus described my invention, I claim:

1. In a lifting jack, a base; a post secured thereto and extending upwardly therefrom; a member revoluble thereon; a nut in the 45 upper end of said revoluble member; a screw in said nut; a weight-supporting head secured to the upper end of said screw; means for guiding said supporting head in its vertical movement; and means for rotating said revoluble member.

2. In a lifting jack, a base; a post secured thereto and extending upwardly therefrom; a member revoluble thereon; a nut in the upper end of said revoluble member; a screw 55 in said nut having a cylindrical bore into which extends the upper end of said post; a weight-supporting head secured to the upper end of said screw; means for guiding said supporting head in its vertical movement; and means for rotating said revoluble member.

3. In a lifting jack, a base; a post secured thereto and extending upwardly therefrom; a member revoluble thereon; a nut in the upper 60 end of said revoluble member; a screw

in said nut; a weight-supporting head secured to the upper end of said screw; means for guiding said supporting head in its vertical movement; a bevel gear on the lower end of said revoluble member; two pinions 70 meshing therewith; a lifting mechanism adapted to actuate one of said pinions; and a brake mechanism adapted to be actuated by the other pinion.

4. In a lifting jack, a base; a post secured 75 thereto and extending upwardly therefrom; a member revoluble thereon; a nut in the upper end of said revoluble member; a screw in said nut; a weight-supporting head secured to the upper end of said screw; means for guiding said supporting head in its vertical movement; a bevel gear on the lower end of said revoluble member; two pinions 80 meshing therewith and diametrically opposed to each other; a lifting mechanism adapted to actuate one of said pinions; and a brake mechanism adapted to be actuated by the other pinion.

5. In a lifting jack, a base; a post extending 90 upwardly therefrom; a tubular member revolvably mounted thereon; a nut secured in the upper end thereof; a screw extending through said nut into said tubular member; a weight-supporting head secured to the upper end of said screw; means for guiding said supporting head in its vertical movement; and means for rotating said revoluble member.

6. In a lifting jack, a base; a post extending 95 upwardly therefrom; a tubular member revolvably mounted thereon; a nut secured in the upper end thereof; a screw extending through said nut into said tubular member; a weight-supporting head secured to the upper end of said screw and provided with 100 a downwardly extending cylindrical portion the lower end of which is fitted to said tubular member; means for guiding said supporting head in its vertical movement; and means for rotating said revoluble member. 105

7. In a lifting jack, a base; a post extending 110 upwardly therefrom; a tubular member revolvably mounted thereon; a nut secured in the upper end thereof; a screw extending through said nut into said tubular member; a weight-supporting head secured to the upper end of said screw; a casing provided with a cylindrical bearing surface for guiding the upper end of said supporting head in its vertical movement; and means for rotating said revoluble member. 115

8. In a lifting jack, a base; a post extending 120 upwardly therefrom; a tubular member revolvably mounted thereon; a nut secured in the upper end thereof; a screw extending through said nut into said tubular member; a weight-supporting head secured to the upper end of said screw and provided 125 with a downwardly extending cylindrical 130

portion the lower end of which is fitted to said tubular member; a casing provided with a cylindrical bearing surface for guiding the upper end of said supporting head 5 in its vertical movement; and means for rotating said revoluble member.

9. In a lifting jack, a base; a post extending upwardly therefrom; a tubular member revolubly mounted on said post; a nut in 10 the upper end thereof; a screw extending through said nut into said tubular member; a weight-supporting head secured to the upper end of said screw; a casing having at its upper end a bearing for said head; a gear 15 secured to the lower end of said tubular member; means for rotating said gear; an annular grooved plate surrounding the hub of said gear; an annular grooved plate superimposed on said base; and anti-friction 20 members interposed between and positioned in the grooves of said plates.

10. In a lifting jack, a base; a post extending upwardly therefrom; a tubular member revolubly mounted on said post; 25 a nut in the upper end thereof; a screw extending through said nut into said tubular member; a weight-supporting head secured to the upper end of said screw; a casing having at its upper end a bearing for said head; 30 a gear secured to the lower end of said tubular member; means for rotating said gear; an annular grooved plate surrounding the hub of said gear; an annular grooved plate superimposed on said base; anti-friction 35 members interposed between and positioned in the grooves of said plates; and an annular band secured to the periphery of one plate and extending into contact with the other plate.

40 11. In a lifting jack, a weight-supporting member; means for raising said weight-supporting member; a shaft adapted to be rotated only during the lowering of the load; an eccentric secured thereto and revoluble

45 therewith; a casing having a cylindrical chamber concentric to said shaft in which said eccentric is adapted to rotate; a piston ring on said eccentric contacting with the cylindrical wall of said chamber; a radial 50 blade extending from said piston member and having a passage therethrough; an oscillating member having a slot through which said blade extends; and a valve adapted to close a passage in said casing from the 55 outer end of said blade to said chamber.

12. In a lifting jack, a weight-supporting member; means for raising said weight-supporting member; a shaft adapted to be rotated only during the lowering of the load; 60 an eccentric secured thereto and revoluble therewith; a casing having a cylindrical chamber concentric to said shaft in which said eccentric is adapted to rotate; a piston ring on said eccentric contacting with the 65 cylindrical wall of said chamber; a radial

blade extending from said piston member and having a passage therethrough; an oscillating member having a slot through which said blade extends; and an oscillating valve adapted to close a passage in said casing from the outer end of said blade to said chamber. 70

13. In a lifting jack, a weight-supporting member; means for raising said weight-supporting member; a shaft adapted to be rotated only during the lowering of the load; 75 an eccentric secured thereto and revoluble therewith; a casing having a cylindrical chamber concentric to said shaft in which said eccentric is adapted to rotate; a piston ring on said eccentric contacting with the cylindrical wall of said chamber; a radial blade extending from said piston member and having a passage therethrough; an oscillating member having a slot through 80 which said blade extends; and a valve adapted to close a passage in said casing from the outer end of said blade to said chamber on the closed side of said blade. 85

14. In a lifting jack, a weight-supporting 90 member; means for raising said weight-supporting member; a shaft adapted to be rotated only during the lowering of the load; an eccentric secured thereto and revoluble therewith; a casing having a cylindrical 95 chamber concentric to said shaft in which said eccentric is adapted to rotate; a piston ring on said eccentric contacting with the cylindrical wall of said chamber; a radial blade extending from said piston member and having a passage therethrough; an oscillating member having a slot through 100 which said blade extends; a cylindrical valve adapted to close a passage in said casing from the outer end of said blade to said chamber; an arm on said valve; and means coacting with said arm for moving said valve about its axis. 105

15. In a lifting jack, a weight-supporting member; means for raising said weight-supporting member; a shaft adapted to be rotated only during the lowering of the load; an eccentric secured thereto and revoluble therewith; a casing having a cylindrical chamber concentric to said shaft in 110 which said eccentric is adapted to rotate; a piston ring on said eccentric contacting with the cylindrical wall of said chamber; a radial blade extending from said piston member and having a passage therethrough; an oscillating member having a slot through 115 which said blade extends; a valve adapted to close a passage in said casing from the outer end of said blade to said chamber; an arm on said valve; a revoluble screw; a nut 120 threaded to said screw and movable endwise thereon during the rotation thereof; and a connection between said nut and arm causing the oscillation of said valve during the reciprocation of said nut. 125

16. In a lifting jack, a weight-supporting member; means for raising said weight-supporting member; a shaft adapted to be rotated only during the lowering of the load; 5 and a hydraulic mechanism coacting with the end of said shaft for preventing the rotation of said shaft when desired and controlling its speed of rotation when permitted to revolve.
17. In a lifting jack, a weight-supporting member; means for raising said weight-supporting member; a shaft adapted to be rotated only during the lowering of the load; an eccentric on said shaft rotatable in a 15 closed chamber; and hydraulic means for controlling the rotation of said eccentric in said chamber.
18. In a lifting jack, a weight-supporting member; means for raising said weight-supporting member; a shaft adapted to be rotated only during the lowering of the load; an eccentric on said shaft rotatable in a 20 closed chamber adapted to be filled with liquid; an annular piston on said eccentric 25 contacting with the cylindrical wall of said chamber and provided with a radial blade; and means for regulating the passage of the liquid from the chamber on one side of said blade to the other side of said chamber.
19. In a lifting jack, a weight-supporting member; means for raising said weight-supporting member; a shaft adapted to be rotated only during the lowering of the load; an eccentric on said shaft rotatable in a 30 closed chamber adapted to be filled with liquid; an annular piston on said eccentric 35 contacting with the cylindrical wall of said chamber and provided with a radial blade having a passage therein communicating 40 with said chamber on one side of said blade; and means for regulating the passage of the liquid from the chamber on one side of said blade to the other side of said chamber.
20. In a lifting jack, a weight-supporting member; means for raising said weight-supporting member; a shaft adapted to be rotated only during the lowering of the load; a casing having a cylindrical chamber 45 adapted to be filled with liquid; a bladed member in said chamber adapted to be actuated by the rotation of said shaft and adapted to prevent the direct circulation of liquid 50 in said chamber from one side of said blade to the other side thereof; and means for controlling the flow of liquid in an indirect 55 passage around said blade.
21. In a lifting jack, a weight-supporting member; means for raising said weight-supporting member; a shaft adapted to be rotated only during the lowering of the load; 60 a casing having a cylindrical chamber concentric with said shaft and partially surrounded by a connecting passage communicating therewith at one end by two communicating 65 passages, said chamber and connect-
- ing passage both containing fluid; an eccentric piston secured to said shaft within said chamber and provided with a radial blade having a fluid passage therein communicating with said chamber; an oscillating member in one communicating passage provided with a diametrical slot through which said blade extends; and a valve in the other communicating passage adapted to control the fluid between said chamber and connecting 70 passage.
22. In a lifting jack, a weight-supporting member; means for raising said weight-supporting member; a shaft adapted to be rotated only during the lowering of the load; 75 a casing having a cylindrical chamber concentric with said shaft and partially surrounded by a connecting passage communicating therewith at one end by two communicating 80 passages, said chamber and connecting passage both containing fluid, an eccentric piston secured to said shaft within said chamber and provided with a radial blade having a fluid passage therein communicating with said chamber; an oscillating member in one communicating passage provided with a diametrical slot through which said blade extends; and an oscillating valve in the other communicating passage adapted to 85 control the fluid between said chamber and connecting passage.
23. In a lifting jack, a weight-supporting member; means for raising said weight-supporting member; a shaft adapted to be rotated only during the lowering of the load; 90 a casing having a cylindrical chamber concentric with said shaft and partially surrounded by a connecting passage communicating therewith at one end by two communicating 95 passages, said chamber and connecting passage both containing fluid; an eccentric piston secured to said shaft within said chamber and provided with a radial blade having a fluid passage therein communicating with said chamber; an oscillating member in one communicating passage provided with a diametrical slot through which said blade extends; and an oscillating valve in the other communicating passage adapted to control the fluid between said chamber and connecting 100 passage.
24. In a lifting jack, a weight-supporting member; means for raising said weight-supporting member; a shaft adapted to be rotated only during the lowering of the load; 105 a casing having a cylindrical chamber concentric with said shaft and partially surrounded by a connecting passage communicating therewith at one end by two communicating 110 passages, said chamber and connecting passage both containing fluid; an eccentric piston secured to said shaft within said chamber and provided with a radial blade having a fluid passage therein communicating with said chamber; an oscillating member in one communicating passage provided with a diametrical slot through which said blade extends; and a valve in the other communicating 115 passage adapted to control the fluid between said chamber and connecting passage; said valve having a port communicating with the fluid passage in said radial blade and another port communicating with said chamber.
25. In a lifting jack, a weight-supporting member; means for raising said weight-supporting member; a shaft adapted to be rotated only during the lowering of the load; 120 a casing having a cylindrical chamber concentric with said shaft and partially surrounded by a connecting passage communicating therewith at one end by two communicating 125 passages, said chamber and connecting passage both containing fluid; an eccentric piston secured to said shaft within said 130 chamber.

chamber and provided with a radial blade having a fluid passage therein communicating with said chamber; an oscillating member in one communicating passage provided with a diametrical slot through which said blade extends; a valve in the other communicating passage adapted to control the fluid between said chamber and connecting passage; and means for adjusting said valve about its axis.

25. In a lifting jack, a weight-supporting member; means for raising said weight-supporting member; a shaft adapted to be rotated only during the lowering of the load; 15 a casing having a cylindrical chamber concentric with said shaft and partially surrounded by a connecting passage communicating therewith at one end by two communi-

cating passages, said chamber and connecting passage both containing fluid; an eccentric piston secured to said shaft within said chamber and provided with a radial blade having a fluid passage therein communicating with said chamber; an oscillating member in one communicating passage provided with a diametrical slot through which said blade extends; a valve in the other communicating passage adapted to control the fluid between said chamber and connecting passage; and means for adjusting said valve about its axis and locking it in adjusted position.

20 25. In testimony whereof I have signed my name to this specification at Boston, Mass., this 31st day of March, 1921.

WALTER E. LOMBARD.
